UNITED STATES PATENT OFFICE.

GEORGE I. ROCKWOOD, OF WORCESTER, MASSACHUSETTS.

APPARATUS FOR OPERATING ALARMS OR OTHER DEVICES.

970,953.

Specification of Letters Patent. Patented Sept. 20, 1910.

Application filed April 17, 1907. Serial No. 368,648.

To all whom it may concern:

Be it known that I, GEORGE I. Rockwood, a citizen of the United States, residing at Worcester, in the county of Worcester and 5 Commonwealth of Massachusetts, have invented a new and useful Improvement in an Apparatus for Operating Alarms or other Devices, of which the following is a specification, accompanied by drawings forming a 10 part of the same, in which—

Figure 1 is a central vertical sectional view of my improved apparatus. Fig. 2 is a sectional view of the receiving chamber on line 2—2, Fig. 1. Fig. 3 is a sectional 15 view of a portion of the receiving chamber on line 3—3, Fig. 1, and Fig. 4 represents one form of an alarm device adapted to be actuated by a flow of liquid.

Similar reference letters and figures refer 20 to similar parts in the different views.

My invention relates to alarms to be used in connection with fire sprinkler systems, or other devices where the alarm is to be operated by the passage of liquid under pressure 25 through a pipe, and is designed to provide for the non-sounding of the alarm by the intermittent variations of pressure of liquid in the pipe, and at the same time to insure the immediate alarm upon the continuous 30 passage of liquid through the pipe, and it consists in the construction and arrangement of parts as hereinafter described and pointed out in the annexed claims.

Referring to the accompanying drawings 35 1 denotes a chamber having an inlet 2 communicating with a water supply under pressure and an outlet 3 communicating with a sprinkler system. Normally the outlet to the chamber 1 is closed, and the liquid under 40 pressure is confined within the chamber, but the device is designed to sound an alarm whenever the outlet is opened by the release of an automatic sprinkler. A check valve 4 is placed in the chamber 1 resting upon a 45 valve seat 5 and designed to be opened by variations in the pressure of liquid on each side thereof in the manner common to check valves of this class.

The face of the valve seat 5 is provided 50 with an annular groove 6, communicating with a pipe 7 leading to a receiving chamber 8, from the top of which a pipe communicates, in the present instance with an electric alarm.

55 A ring 9 is held in the chamber 8 having an integral diametrical bar 9^a provided with

an inlet water passage 10 communicating with the supply pipe 7 and having an inlet opening 11, into the chamber 8, and also with an outlet water passage 12 communicating with a waste pipe 13 and having an outlet opening 14 from the chamber 8. The inlet and outlet openings 11 and 14 are preferably placed one over the other, and they are provided with valve seats 15 and 16, to receive 60 valves 17 and 18. The valve 17 is carried by a diaphragm 19 which is held at its edges by the walls of the chamber 8 below the ring 9 and forms a yielding false bottom for the chamber, normally held in a raised position 65 by a spring 20, with the valve 17 in contact with the valve seat 15, thereby normally closing the inlet passage 11. The valve 17 is provided with curved elastic arms 21 to which is attached the valve 18 normally 70 held out of contact with the valve seat 16; but arranged to close the outlet 14 whenever the valve 17 is depressed to open the inlet 11. The diaphragm 19 carries on its lower side a washer 22, which contacts at 23 with the bottom of the chamber when the valve 17 is depressed sufficiently to open the inlet 11 to its full capacity and thereby prevent any 75 injury to the diaphragm by excessive pressure. During any downward movement of 80 the valve 17, less than the complete depression of the diaphragm, the inflowing liquid is throttled by a boss 24 mounted on the valve 17, which restricts the flow of liquid to the annular space around the boss 24 until 85 the further depression of the valve withdraws the boss from the inlet 11. Communicating with the outlet passage 12 is a stand-pipe 25 closed at the top except for the small vent hole 26 near the top of the 90 chamber 8.

For the purpose of illustrating the practical application of my invention to the purpose of sounding an alarm I have shown an electric alarm apparatus, comprising two 100 binding posts, 27 and 28, forming part of an electrical circuit capable of producing preferably an audible alarm, as by a bell 29. The circuit is completed by a blade 29^a pivotally connected to one of the posts and arranged to be swung into contact with the other by a block 30, supported on a flexible diaphragm 31, which is raised by the pressure of liquid in the chamber 8 through a pipe 32. 105

The chamber 8, instead of, or in addition to, communicating with an electric alarm,

may communicate with an alarm apparatus adapted to be operated by a continuous flow of water, comprising a liquid motor, such for example, as a rotating bucket wheel 33 inclosed in a casing 34 and rotated by a stream of liquid from the chamber 8 through a spout 35.

The operation of my device is as follows:—
10 The check valve 4, in the normal condition of the sprinkler system, rests upon the valve seat 5 shutting off the flow of the liquid through the pipe 7; the valve 17 likewise remains closed by the spring 20, with the valve 18 raised by the elastic arms 21. In this
15 position of the valves, if the outlet 3 is opened by the release of one or more sprinklers in the system, the check valve 4 is raised, allowing liquid to flow through the pipe 7, and apply the pressure of the system against
20 the valve 17 causing a slight depression of the valve, sufficient to allow a throttled flow of liquid to take place through the annular space around the boss 24, and at the same time closing the outlet 14. The chamber 8
25 thereupon fills, until a predetermined point has been reached, depending upon the tension of the spring 20 when the pressure of the liquid in the chamber 8, exerted upon the upper surface of the diaphragm 19,
30 forces the valve 17 wide open, the arms 21 yielding for the purpose, permitting a flow of liquid equal to the full capacity of the inlet 11, and sufficient to actuate a liquid motor such as shown in Fig. 4.
35 In case the check valve is spasmodically opened and closed as in the case of a water hammer, the pressure applied momentarily to the valve 17 serves to slightly open the valve 17 and close the valve 18, allowing a
40 limited amount of liquid to enter the chamber 8, when the removal of pressure from the valve 17, by the closing of the check valve 4 causes the spring 20 to immediately close valve 17 and open valve 18 which empties
45 the chamber down to the valve seat 16, the liquid below the valve seat 16 remaining permanently in the chamber 8. Under whatever conditions the check valve 4 is raised, whether by a water hammer, or by the release of an automatic sprinkler, the pressure of the liquid in the system is applied to the valve 17, which immediately closes the outlet valve 18, checking the flow of liquid
50 from the chamber and permitting a throttled flow of liquid into the chamber, which continues as long as the check valve 4 remains open; but the instant the check valve closes the valve 17 is relieved from the pressure of liquid in the system, and is closed by the
55 spring 20. The closing of the valve 17 opens valve 18 and allows the liquid to flow out of the chamber. In the event of a water hammer only a comparatively small quantity of liquid flows into the chamber 8, but in case
60 an automatic sprinkler is released, the flow
65

of liquid into the chamber 8 continues, until a predetermined point is reached, when the pressure of the liquid in the chamber 8 acting upon the upper surface of the diaphragm 19 and in conjunction with the pressure from the system exerted upon the valve 17, opens the valve 17 to its full extent and allows a free flow of liquid through the inlet 11, sufficient to rotate a motor, such as the bucket wheel 33 which may be operatively connected with an alarm in the manner now practiced in alarm devices of this class. By my invention, I therefore secure two characteristic results, among other advantages, namely, I limit the flow of liquid into the chamber 8 in the case of a water hammer and prevent an undue waste of liquid, and I secure a full and free flow of liquid whenever the chamber fills to a certain point, and thereby secure an effective force to actuate a rotating alarm device. My apparatus is moreover absolute and positive in its action. The opening of the inlet valve to admit liquid to the chamber 8 closes the outlet valve and vice versa, while the continued depression of the inlet valve by means of the additional hydrostatic pressure in the chamber 8 exerts an additional pressure upon the outlet valve 18 equal to the elastic resistance of the arms 21.

95 I claim,

1. The combination of a receiving chamber having inlet and discharge openings, a supply passage communicating with said inlet opening, a valve at said inlet opening arranged to be opened by pressure of liquid in said supply passage, a valve at said discharge opening arranged to be closed upon the opening of said inlet valve, and means operated by a predetermined amount of liquid in said receiving chamber for increasing the size of said inlet opening.

2. The combination of a receiving chamber having inlet and discharge openings, valves for said openings, with the valve for said discharge opening arranged to be closed when the valve for said inlet opening is opened, a liquid supply passage communicating with said inlet opening arranged to open said inlet valve by pressure of liquid in said passage, and means operated by liquid in said chamber for still further opening said inlet valve.

3. The combination of a receiving chamber having inlet and discharge openings, valves for said openings, with the valve at said discharge opening arranged to be closed as soon as the valve at said inlet opening is opened, a liquid supply passage communicating with said inlet opening, a valve at the other end of said supply passage, upon the opening of which the pressure in said supply passage is increased, thereby opening said inlet valve and closing said exit valve, and means for still further opening

said inlet valve by the entrance of a predetermined amount of liquid into said chamber.

4. The combination with a receiving chamber, a liquid supply-system under pressure, 5 a passage connecting said supply-system and said chamber, means for normally closing the receiving end of said passage, a valve closing the delivery end of said passage, a boss carried by said valve and entering the 10 delivery end of said passage, and a spring for holding said valve normally in a closed position.

5. The combination of a receiving chamber having inlet and discharge openings, 15 valves for said openings, an elastic connection between said valves arranged to close the discharge valve by opening the inlet valve, a liquid supply passage communicating with said inlet opening arranged to open 20 said inlet valve by the pressure of liquid in said passage, and means for still further opening said inlet valve by the increased amount of water in said chamber, thereby also exerting increased pressure to hold said 25 exit valve closed.

6. The combination with a liquid supply system under pressure, of a receiving chamber, a passage connecting said supply system and said chamber, an inlet valve between 30 said chamber and said passage, normally closed, but arranged to be opened by increase of pressure in said passage, a discharge opening for said chamber with a valve for said opening, normally open, but 35 arranged to be closed whenever said inlet valve is opened, and a valve between said supply system and said passage arranged by its opening to increase the pressure in said passage.

40 7. The combination with a receiving chamber and a liquid supply-system under pressure, of a passage connecting said supply-system and said chamber, an inlet valve closing said passage, a spring holding said inlet valve in a closed position, an exhaust passage from said chamber, an outlet valve for closing said exhaust passage, a yielding connection between the outlet and inlet valves, whereby said outlet valve is closed synchronously with the opening of said inlet valve. 50

8. The combination with a receiving chamber and a liquid supply-system under pressure, of a supply passage connecting said chamber and said supply-system, an exhaust passage for said chamber, an inlet valve for 55 said supply passage, an outlet valve for said exhaust passage, and a yielding connection between said valves.

9. The combination of a receiving chamber having an inlet opening, a supply passage communicating with said opening, a valve at said opening arranged to be partially opened by the pressure of liquid in said supply passage, a spring acting upon said valve to resist its complete opening by 60 said pressure, and means acted upon by a predetermined amount of water in said chamber for completing the opening of said valve against the pressure of said spring.

10. The combination with a receiving 70 chamber, of a diaphragm forming a false bottom for said chamber, an inlet passage, a valve carried by said diaphragm and closing the delivery end of said inlet passage, a spring with its tension applied to hold said 75 valve in a closed position, means for normally closing the receiving end of said inlet passage, an outlet passage, and means for synchronously closing said outlet passage when said inlet passage is opened. 80

11. The combination of a receiving chamber, inlet and outlet passages, a diaphragm in said chamber below said inlet and outlet passages, a spring actuated valve attached to said diaphragm for closing said inlet passage, a valve arranged to close said outlet passage, and a yielding connection between said inlet and said outlet valves. 85

12. The combination with a receiving chamber, of a ring held in said chamber, 90 provided with an integral diametrical bar containing inlet and outlet passages opening into said chamber on opposite sides of said bar, and a pair of connected valves for closing said passages.
